UNITED STATES PATENT OFFICE.

HARRY J. HINCHEY, OF ATLANTA, GEORGIA, ASSIGNOR TO WRIGHT-AUSTIN COMPANY, OF DETROIT, MICHIGAN, A CORPORATION OF MICHIGAN.

STEAM-TRAP.

1,396,206.

Specification of Letters Patent.

Patented Nov. 8, 1921.

Application filed August 2, 1919. Serial No. 314,943.

To all whom it may concern:

Be it known that I, HARRY J. HINCHEY, a citizen of the United States of America, residing at Atlanta, in the county of Fulton and State of Georgia, have invented certain new and useful Improvements in Steam-Traps, of which the following is a specification, reference being had therein to the accompanying drawings.

10 The invention consists of a steam trap designed to operate under a very wide range of pressures and which will handle a maximum volume of water for a given size of trap; and it consists in the employment of a 15 Venturi tube in the return passage and in the combination and arrangement of the various parts as hereinafter more specifically described.

In the drawings,

20 Figure 1 is a vertical, central, longitudinal section through a trap embodying my invention;

Fig. 2 is a section on line $x-x$ of Fig. 1; and

25 Fig. 3 is a detail section on line $y-y$ of Fig. 1.

I have shown my invention applied to the well-known type of bucket trap, with some modifications: A representing the casing, 30 the interior of which forms the water receptacle for the water and steam finding inlet through the opening B. In this water receptacle is a bucket, C, hinged at D to a lug, E, preferably carried by the top F. G is an outlet opening in the top, to which is 35 connected the depending pipe, H, which extends to near the bottom of the bucket C. This bucket is preferably provided with a well a , so that the bucket will be most thoroughly cleared out in the return operation 40 of the water.

I may have any suitable means of determining the movement of the bucket C; a set screw I being shown passing through 45 the bottom of the casing, against which the bucket will drop in its lower position. This lower position can be determined by raising and lowering the set screw.

In the return connection from the trap, I 50 arrange a Venturi tube. In this embodiment of my invention I have shown the Venturi tube as formed in the top F of the casing, at G, there being a full-size tubular inlet, b, at one end connecting with the 55 pipe H, and an outlet, c, at the other end,

I have found that in order to get the best results which I have so far obtained with this Venturi tube, the inlet portion of the tube, which I have here letter d, should have a length equal to twice the diameter of the 60 pipe size, and the outlet portion, e, four times the diameter of the pipe size. The best proportion for the throat of the Venturi tube depends upon the size of the pipe, but for one-half inch ($\frac{1}{2}$ ") pipe, I preferably 65 use a seven-thirty-second inch ($\frac{7}{32}$ ") throat, for one inch (1") pipe, eleven-thirty-second inch ($\frac{11}{32}$ ") throat; and substantially such ratio for the other sizes, although the exact size, as before stated, can best be determined by actual test.

I prefer to have a valve controlling the exit water from the water receptacle, which I preferably locate at the throat of the Venturi tube. At the throat in my present construction, I have shown a cross-bore, J, in which is placed a valve, K, preferably cylindrical and which is secured by a suitable connecting rod, L, with the bucket C. This valve is provided with an aperture, h, which, 75 when the bucket drops, is alined with the throat of the Venturi tube, and when it rises, is out of alinement therewith. I have shown in the valve some annular grooves, i, 80 on either side of the port, which act as sealing rings or sealing grooves for the valve.

I have shown a passage, N, leading from the top of the water receptacle to the top of the port J, so as to counterbalance the pressure on the valve. This I have illustrated in 90 Fig. 3.

The operation of the device is as follows:

The steam entering through the passage B, preferably strikes some deflector to keep it from going directly into the bucket; 95 which deflector may be the bracket or lug E. As the water accumulates in the water receptacle, it will finally rise above the level of the bucket and flow therein until it has overcome the buoyancy of the bucket, when 100 the bucket will drop against the stop, I, and the valve will be correspondingly lowered to register the port, h, with the throat of the venturi. The steam pressure within the tank will then force the water out 105 through the pipe H, opening the passage-way, a and b, and through the venturi to the desired receptacle for the water of condensation.

I find that with this construction of trap, 110

a single trap of given size will operate to discharge the maximum quantity of water through a practically unlimited range of pressures. This operation is made possible 5 by reason of the venturi and the valve at the throat of the venturi, whereby with the maximum discharge of water, the exposed area of the valve is the minimum, so that the pressure exerted upon the valve by the dis- 10 charging water is the minimum when the valve is being closed. Thus the valve may be more easily opened. The construction is also simple, cheap to manufacture, and capable of operating for a long period of time 15 with a minimum of wear.

The drawing filed herewith is practically to scale, one-half size, of an actual trap constructed by me.

I claim—

- 20 1. In a steam trap, the combination with the water chamber of a return passage therefrom, a Venturi tube in said return passage and a valve at the throat of said Venturi tube.
- 25 2. In a steam trap, the combination with the water chamber, of a return passage therefrom, a Venturi tube in said return passage, and a balanced valve at the throat of said Venturi tube.
- 30 3. In a steam trap, the combination with

the water chamber thereof, a movable bucket therein, an outgoing tube depending into said bucket, a Venturi tube in the return passage connected with said outgoing tube, and a valve at the throat of the venturi, 35 controlled by said bucket.

4. In a steam trap, the combination with the body having a chamber therein, an incoming connection thereto, a movable bucket therein, an outgoing pipe connected to the top and depending into the bucket, a passage across the top into which the depending pipe connects, a Venturi tube in said top passage, a valve at the throat of the venturi, 40 and a connection from the bucket to said valve. 45

5. In a steam trap, the combination with the water chamber, of a return passage therefrom including a tubular portion and a Venturi portion, said Venturi portion having its inlet portion of a length approximately twice the diameter of said tubular portion and also having its outlet portion of a length approximately four times the diameter of said tubular portion, and a 50 valve at the throat of said Venturi portion.

In testimony whereof I affix my signature.

HARRY J. HINCHEY.
